UNITED STATES PATENT OFFICE

BRUCE FORD, OF PHILADELPHIA, PENNSYLVANIA

FILLING-VENT STRUCTURE FOR STORAGE BATTERIES

Application filed March 29, 1926. Serial No. 98,317.

The principal object of the present invention is to obviate the necessity of boring or drilling operations and to provide for producing the necessary parts and ducts by molding operations.

Another object of the invention is to simplify and cheapen the construction of such structures without detriment to the performance by them of their functions.

10 Other objects of the invention will appear from the following description at the end of which the invention will be claimed.

In the following description reference will be made to the accompanying drawings forming part hereof and in which

Figure 1 is a central sectional view of a filling vent structure embodying features of the invention.

Fig. 2 is a similar view illustrating a modification.

Fig. 3 is a sectional view taken on the line 3—3 of Fig. 2 with the stopper or plug omitted.

Fig. 4 is a top view of Fig. 3.

25 Figs. 5 and 6 are a central section and bottom plan view of another modification.

Figs. 7 and 8 are views similar to Figs. 5 and 6 of another modification, and

30 Figs. 9 and 10 are views similar to Figs. 5 and 6 of another modification.

Referring to the drawings, more particularly Fig. 1, 1 is a horizontal cover. 2 is a chamber above, and 3 is a chamber below the cover and they intercommunicate and are in offset relation to each other. 4 are vertical vent ducts perforating the offset portion whereby the interior of the top chamber 2 is connected with or is in communication with the exterior of the bottom chamber. As shown the chambers 2 and 3 are provided by a tubular structure extending above and below the cover and of which the upper end portion receives a suitably vented plug and of which the lower end portion extends toward or dips below the level of the electrolyte not shown because too well understood.

It may be remarked that gas, vapor or the like carrying spray escapes from above the level of the electrolyte through the vents 4 to the chambers 2 and 3 where they deposit

the spray which falls back into the electrolyte, the gas escaping at the vented plug.

It is a feature of the described construction that the vent duct or ducts 4 as well as the rest of the cover structure are capable of being molded without drilling or boring. For example, the ducts may be produced by pins, projections or cores provided on one-half of the mold. The walls 5 and 6 of the tubular structure or of the chambers 2 and 3 are offset in respect to each other and the vertical vent duct 4 extends through the offset portion and through the cover or, perhaps more accurately, past the cover.

The construction and mode of operation of the modification illustrated in Figs. 2-4 are substantially as described in connection with Fig. 1 except that the offset occurs at two points 7, and the ducts 4^a extend through the offset portion and also through a portion of the bounding wall of the cylindrical chamber 3.

The construction and mode of operation of the modification shown in Figs. 5 and 6 are as above described except that the offset is provided by an eccentric arrangement of the upper and lower chambers 2^a and 3^a.

The construction and mode of operation of the modification shown in Figs. 7 and 8 are as above described except that the offset is provided by flattening the wall of the chamber 3^b.

The construction and mode of operation of the modification shown in Figs. 9 and 10 are as above described except that the offset is provided by warping the walls of the chamber 3^c inward at two points.

It will be obvious to those skilled in the art to which the invention relates that modifications may be made in details of construction and arrangement and in matters of mere form without departing from the spirit of the invention which is not limited to such matters or otherwise than as the prior art and the appended claims may require.

90 I claim:

1. A filling vent structure for storage batteries including a horizontal cover, intercommunicating chambers having imperforate bounding walls and arranged in offset rela- 100

tion to each other and of which one is above the cover and of which the other is below the cover, and a vertical vent duct perforating the offset portion whereby the interior of the upper chamber is connected with the exterior of the bottom chamber.

2. A filling vent structure for storage batteries including a horizontal cover, inter-communicating vertical tubular chambers of which one is arranged above the cover and of which the other is arranged below the cover, said chambers having imperforate walls offset in relation to each other, and a vertical vent duct extending through the offset portions and connecting the interior of the upper chamber with the exterior of the lower chamber.

BRUCE FORD.
